CLAIM

The ornamental design for a developer powder container, substantially as shown and described.

DESCRIPTION

FIG. 1 is a top plan view of a developer powder container showing my new design;
FIG. 2 is a front elevational view thereof, the rear being substantially a mirror image thereto;
FIG. 3 is a bottom plan view thereof;
FIG. 4 is a left end elevational view thereof;
FIG. 5 is a right end elevational view thereof.

*FIG. 1**FIG. 2**FIG. 3*

FIG. 4
